UNITED STATES PATENT OFFICE.

CHARLES E. HASTY, OF CLEVELAND, OHIO, ASSIGNOR OF SIXTY-SIX AND TWO-THIRDS PER CENT. TO ADOLPH NEWMAN AND WAYNE O. CONGER, BOTH OF CLEVELAND, OHIO.

TUBE-BEADING DEVICE.

1,326,195.

Specification of Letters Patent. Patented Dec. 30, 1919.

Application filed May 17, 1917. Serial No. 169,268.

To all whom it may concern:

Be it known that I, CHARLES E. HASTY, a citizen of the United States, residing at Cleveland, in the county of Cuyahoga and 5 State of Ohio, have invented a certain new and useful Improvement in Tube-Beading Devices, of which the following is a full, clear, and exact description.

This invention relates to a device for 10 beading or flanging over the ends of boiler tubes which have been inserted through a flue plate. The object of the invention is to produce a device which will properly position an air gun or equivalent instrument 15 so that it may deliver a properly directed blow to the end of the tube, and as the gun is moved around the end of the tube, maintain the air gun in its proper position.

A further object of the invention is to 20 produce a device of the character which will obviate the necessity of the operator twisting his arm in moving the air gun into its succession of positions in riveting.

Further objects will appear as the description 25 proceeds. Generally speaking, the invention may be said to comprise the elements and combinations thereof set forth in the accompanying claims.

Reference should be had to the accompanying drawings forming a part of this 30 specification, in which Figure 1 is an elevation with portions in section of a device forming the subject matter of my invention in position to operate; Fig. 2 is a section 35 upon the line 2—2 of Fig. 1 looking in the direction of the arrow; Fig. 3 is an end elevation of an expansible bushing; Fig. 4 is a sectional plan view showing a detail of construction.

Referring to the drawings, 1 indicates a 40 flue plate and 2 a tube which extends through an opening in the flue plate, the end of which tube is to be beaded or flanged so as to be retained by the flue plate.

Within the tube 2 there is an expansible 45 bushing, generally represented at 3. This expansible bushing consists of four parts which will be seen in Fig. 3. The parts are provided with grooves, such as indicated 50 at 4, which grooves are in alinement and within the grooves there is a spring 5 which normally acts under compression to pull the various elements of the expansible bushing 55 toward each other. The expansible bushing has a central opening generally indicated at

6, which is a tapered opening and is provided with screw threads.

Adjacent one end of the bushing the various parts thereof are provided with an extension such as indicated at 7 in Fig. 1. 60 This extension is adapted to fit within a depressed portion which is formed in the tube 2 by the expansion of a shoulder 8.

This shoulder is previously formed in the tube, and forms an abutment which engages 65 with the inner side of the flue plate so as to hold the tube against movement when the outer end of the tube is being beaded or flanged over.

The expansible bushing is supported upon 70 a member 9 which at one end is conical in shape and screw threaded as indicated at 10, this conical screw threaded portion being adapted to coöperate with the segments of the expansible bushing for the purpose 75 of expanding the same or permitting their retraction. The member 9 extends beyond the bushing and at its end has a squared portion 11 by which the member 9 may be turned.

At the threaded end of the member 9 there is a post 12 which extends through an opening in a plate 13 that bears against the ends of the sectional bushing. Upon the 80 end of the rod there is a nut 14 and between the nut and plate there is a spring 15. The purpose of this arrangement is to prevent the sections of the expansible bushing from moving with the threaded portion of the member 9 as it is turned.

Upon the member 9 and beyond the threaded portion there is a tubular member 16 which at its inner end is provided with a plurality of pins 17 which pins engage in elongated slots 18 formed in the ends of the 95 expansible bushing members. The tubular portion 16 has a reduced end and upon this reduced end there is mounted a sleeve 18 which is free to turn upon the tubular member 16. Depending from the sleeve is an 100 arm 19 which receives the end of a rod 20, the end of the rod being secured into the arm 19. The opposite end of the rod 20 engages with a depending portion 21 of a sleeve 22. This sleeve is a split sleeve and 105 is adapted to encircle the casing 23 of an air gun or similar device. The parts of the split casing are secured and held by means of bolts 24 which extend through lip portions of the sleeve 22.

110

The end of the rod 20 receives a nut 24^a which bears against the portion 21 of the sleeve 22, and holds it in position upon the rod. Upon the casing 23 there are collars 25 which lie upon opposite sides of the sleeve 22, these collars hold packing such as indicated at 26, the packing lying against the sleeve and holding the sleeve against rattling or jarring as the air hammer is operated.

Supported upon the upper portion of the sleeve 18 is a guiding member 27. This guiding member is formed in two parts which parts are secured together by a wing nut 28. The member 27 has angular sides and receives an angular sided tool 29 which tool is operated by the air gun or similar mechanism within the casing 23. The tool 29 has a suitable head adapted to engage with the end of the tube to be beaded, and as the tool 29 is reciprocated, in a manner well known, the end of the tube will be flanged over. The member 27 is pivoted upon the sleeve as indicated in the drawing, so that this member may assume an angular position with respect to the sleeve 18 upon which it is mounted.

The rod 20 is formed with overlapping portions 20^a. These overlapping portions 30 have an opening through them which is occupied by a bolt 27^w. The bolt is squared at one end as indicated at 28^x. This squared portion lies within a squared opening formed in one of the portions of the rod. The other 35 portion of the bolt is rounded and receives upon the outer threaded end a wing nut 29^y. Surrounding the bolt is a plate 30 provided with projections or depressions which are adapted to coöperate with similar projections or depressions formed upon the inner portion of the wing nut.

The two parts of the rod 20 may be adjusted at an angle with respect to each other by loosening the wing nut 29 which permits 45 relative movement of the two parts of the rod 20. The tightening of the wing nut will hold the two portions in their adjusted angular position.

This construction is made use of, to vary 50 within limits the angular relationship of the tool 20 to the work.

In operating the device the hand of the operator may grasp the handle of the air gun, and without twisting the arm of the operator the air gun may be moved in a circular path so that the tool 29 is in succession presented to different portions of the end of the tube. The swivel mounting of the sleeve 18 and the sleeve 22 permit of this movement.

Because the arm of the operator does not need to be twisted it is possible for the operator to effect a much better job of beading than would be possible under other circumstances.

Having described my invention, I claim:—

1. In a tube beading device, a supporting member adapted to be mounted in a tube to be beaded, a hammer casing, a supporting means for the hammer casing said supporting means being free to turn upon the supporting member, the hammer casing being free to turn axially with respect to its supporting means.

2. In a tube beading device, a supporting member adapted to be mounted in a tube to be beaded, a hammer casing mounted off center with respect to the supporting member, and supporting means between the supporting member and the hammer casing said supporting means having an axially swivel connection with the supporting member and with the said hammer casing.

3. In a tube beading device, a supporting member adapted to be mounted in a tube to be beaded, a sleeve swiveled thereon, an arm secured to said sleeve, a hammer casing, a second sleeve swiveled on said hammer casing, the second sleeve being secured to the arm, and means carried by the first sleeve for guiding a tool.

4. In a tube beading device, a supporting member adapted to be mounted in a tube to be beaded, a sleeve mounted upon the supporting member and free to turn thereon, a second sleeve, a spacing member secured at its opposite ends to the said sleeves to hold said sleeves in definite relationship, a hammer casing, the second sleeve being mounted upon said casing, and permitting relative rotation between this sleeve and hammer casing, and a support carried by the first sleeve adapted to receive a hammer.

5. In a tube beading device, the combination with a supporting member adapted to be mounted in a tube to be beaded, a sleeve member free to turn upon said support, said sleeve member having a depending portion, a rod secured at one of its ends to said depending portion of the sleeve, a second sleeve member having a depending portion the other end of said rod being secured to the said depending portion of the second sleeve, a hammer casing, the second mentioned sleeve being supported upon the said hammer casing but free to move axially with respect thereto.

6. In a tube beading device, a supporting member adapted to be mounted in a tube to be beaded, a sleeve mounted upon the said supporting member, a hammer casing, a sleeve mounted upon said hammer casing, a rod connecting the said sleeves said rod being formed in two parts, and means for securing them in adjusted angular position with respect to each other.

7. In a tube beading device, a supporting member adapted to be mounted in a tube to be beaded, a sleeve supported upon said member and free to turn thereon, a hammer

casing, a sleeve supported upon said hammer casing and free to turn thereon, means engaging opposite ends of said sleeve upon the hammer casing, packing between the 5 said member and the sleeve, and a rod at its opposite ends secured to the said sleeves.

8. In a tube beading device, a rod having a tapered threaded portion, an expansible bushing adapted to coöperate with said 10 threaded end portion, a tubular member upon the rod said tubular member being provided with pins adapted to engage in slots formed on the end of the expansible bushing, a sleeve member mounted upon the 15 tubular member and free to turn thereon, means carried by the rod for holding the sleeve member on the tubular member, and

means associated with the sleeve member for supporting a hammering device.

9. In a tube beading device, a rod adapted 20 to be supported within a tube to be beaded, a sleeve mounted upon the rod and free to turn thereon, a tube supporting member mounted upon the said sleeve said tube supporting member being pivoted, a hammer 25 casing, a sleeve upon the hammer casing free to turn thereon, a rod connecting the said sleeves said rod being formed in two parts with means for holding the said parts of the rod in adjusted position. 30

In testimony whereof I hereunto affix my signature.

CHARLES E. HASTY.
